CASING FOR A THERMOSTAT, OR THE LIKE

Earl W. Claus, Kirkwood, Mo., assignor to White-Rodgers Company, St. Louis, Mo., a corporation of Delaware

Application December 22, 1958, Serial No. 53,860

Term of patent 14 years

(Cl. D52—7)

FIG. 2

FIG. 1

FIG. 3

FIG. 4

Fig. 1 is a front elevation of a casing for a thermostat, showing my new design;

Fig. 2 is a plan view thereof;

Fig. 3 is a side elevation thereof; and

Fig. 4 is a bottom view thereof.

The undisclosed side of the thermostat casing is substantially the same in appearance as the side shown in Fig. 3.

I claim:

The ornamental design for a casing for a thermostat, or the like, substantially as shown and described.
